JOHN P. RATHBUN, OF MOORES, PENNSYLVANIA, ASSIGNOR TO WESTINGHOUSE ELECTRIC & MANUFACTURING COMPANY, A CORPORATION OF PENNSYLVANIA

HEAT EXCHANGER

Application filed March 29, 1928. Serial No. 265,635.

My invention relates to heat exchangers of the open type, such as jet heaters, or jet condensers, and more particularly to jet heaters for electro-chemical processes, and it has for 5 an object to improve the efficiency of apparatus of this character.

In those electro-chemical processes which involve electrolysis, such for example, as the electrolytic refining of metals, electro-plating, and the like, it is desirable to supply electrolyte at the temperature at which the process may best be carried on. In the refining of copper this temperature is around 140° F., and, consequently, some heating is required. Jet heaters have several characteristics which make them especially well suited to this work, such, for example, as their high thermal efficiency and their capacity to create sufficient vacuum to lift the electrolyte to 20 the nozzle chamber, or, in other words, to pull it into the heater.

However, in these various processes it is desirable to maintain the air, or oxygen content of the electrolyte as low as possible because of the tendency of this gas to cause metal building. For instance, in the refining of copper, the liberation of any appreciable quantity of oxygen between the electrodes will cause copper building, which soon extends from one electrode to another, causing 25 a short circuit.

As liquid media flows from a jet heater into a tail pipe, or other discharge, or outlet connection, the lines of flow necessarily converge 30 toward the outlet, and this convergence of flow tends to produce an entraining action in the vicinity of the outlet. As a result of this action, air, oxygen, or other gaseous media in the vicinity of the outlet is entrained to a greater, or less extent, depending upon the 35 conditions of flow. This condition becomes even more aggravated with the occurrence of surges, or fluctuations which leave the outlet only partially submerged, for, when the latter 40 condition exists, a considerable quantity of gaseous media may be entrained during a relatively brief interval. This entrainment of gaseous media is objectionable in various processes, such, for example, as in the electrolytic refining of copper, in which the presence 45

of occluded gases in the electrolyte, or other heated media, is detrimental.

More particularly, therefore, an object of my invention is to provide means for preventing gaseous media from being drawn into 55 the tail pipe, or other discharge connection of a jet heater.

This and other objects are effected by my invention, as will be apparent from the following description and claims taken in connection with the accompanying drawings, forming a part of this application, in which the single figure is a sectional elevation of a 60 jet heater.

In accordance with my invention, I provide a liquid seal about the discharge connection to a jet heater. I have found that this arrangement effectively prevents gaseous media from becoming entrained in the liquid 65 media discharged from the heater.

In the drawing I show a jet heater, indicated generally at 10, and comprising a mixing chamber 11 and a collection and discharge chamber 12, the latter having an outlet 13 adapted to be connected to a tail pipe, or other discharge connection (not shown). Liquid media, such as service water, which may be an electrolytic solution, is supplied through the inlet 14 to the nozzle chamber 16 from which it passes through 70 the nozzles 17 into the mixing chamber 11.

Gaseous media, such as steam, or other heating vapor, is passed into the mixing chamber 11 through the inlet 18, and in passing downwardly therethrough becomes 75 thoroughly mixed with the liquid media issuing from the nozzles 17, with the result that this heating media becomes condensed and thus, gives up its latent heat to the resulting mixture of liquid media, which latter 80 is discharged through the converging passage provided by the converging walls 19. An air and non-condensable gas removal connection 22 may also be provided in the upper portion of the wall of the discharge chamber 12 for removing air and other non-condensable gases from this chamber.

The apparatus, thus far referred to, is well known in the art and is, therefore, only briefly described. When apparatus of this 100

character is used for heating a solution of electrolyte, it will readily be seen that the convergence of flow of the liquid media passing from the chamber 12 through the 5 outlet 13 will produce an entraining action which will be augmented by any fluctuations which leave the outlet 13 only partially submerged. In this way, air, oxygen, or other gaseous media may become entrained and 10 pass with the liquid media through the outlet 13 and into the tail pipe, or other discharge connection. In order to prevent occurrences of this kind, I provide a liquid seal 15 about the outlet 13.

15 This liquid seal is formed by providing an upstanding wall 23 about this outlet and spacing the cowl 24 above the outlet. The cowl 24 preferably has its upper portion of a conical, or other suitable shape, and the 20 lower portions of the cowl depend about the upstanding wall 23 in encompassing relation therewith, thereby providing upstanding columns or legs 30 and 31 disposed concentrically about the outlet 13 for retaining liquid.

25 The cowl 24 may be supported in any suitable manner as, for example, by means of the supporting strips 26, which may be made integral with the wall 23 as shown. I also provide a number of reinforcing webs 28 about the inner 30 walls of the base of the discharge chamber for reinforcing the latter.

It will be apparent that, by arranging the cowl 24 above the outlet 13, I have provided an effective means for preventing gaseous media, which may be in the chamber 12 above the level of the liquid media therein, from becoming entrained and passing through the outlet 13.

In the operation of my heater, a solution 40 of electrolyte is passed through the inlet 14 into the nozzle chamber 16, from which it is supplied to the nozzles 17, and a heating medium, such as steam, is passed into the mixing chamber 11 through the inlet 18. The 45 resulting mixture is then discharged into the collection and discharge chamber 12 where, by virtue of the liquid seal, the entraining action of the liquid media passing through the outlet 13 becomes ineffective and thus, it 50 is assured that gaseous media, such as air and other non-condensable gases, will be prevented from passing through the outlet 13.

It will readily be seen, therefore, that I have provided a simple and efficient means 55 for adapting a jet heater to the service of heating solutions, such as electrolyte, where the presence of any appreciable quantity of occluded gases would be very detrimental.

While I have shown my invention in but 60 one form, it will be obvious to those skilled in the art that it is not so limited, but is susceptible of various changes and modifications without departing from the spirit thereof, and I desire, therefore, that only such 65 limitations shall be placed thereupon as are

imposed by the prior art or as are specifically set forth in the appended claims.

What I claim is:—

1. In heating apparatus of the contact type, the combination of a casing embodying a chamber for mixing heating media and media to be heated, a discharge chamber disposed below the mixing chamber, a circular, converging passageway depending from the mixing chamber into the discharge chamber for conveying the commingled media thereto, an outlet for gaseous media provided in an upper portion of the discharge chamber, an outlet for liquid media disposed in a lower portion of the discharge chamber, and liquid sealing means associated with the liquid media outlet and disposed within the casing for restricting the passage of gaseous media to said gaseous media outlet. 75

2. In heating apparatus of the contact type, the combination of a casing embodying a mixing chamber, an inlet communicating with the mixing chamber for admitting heating media thereto, a plurality of inlets disposed circumferentially about the heating media inlet for admitting liquid media to be heated to the mixing chamber, a discharge chamber embodied in the casing and disposed below the mixing chamber, a passageway depending from the mixing chamber into the discharge chamber for conveying commingled media thereto, an outlet for heated liquid provided in a lower portion of the discharge chamber, an outlet for gaseous media provided in the discharge chamber and disposed laterally of said depending passageway, and liquid sealing means associated with said heated liquid outlet and disposed within the casing for restricting the passage of gaseous media to said gaseous media outlet. 85

3. In heating apparatus of the contact type, the combination of a casing embodying a chamber for mixing heating media and media to be heated, a discharge chamber freely communicating with the mixing chamber for receiving the commingled media therefrom, separate outlet means communicating with the discharge chamber for the removal of gaseous media and for the removal of liquid media, and liquid sealing means associated with the liquid outlet means for restricting the removal of gaseous media to said gaseous media outlet means, said liquid sealing means embodying a leg through which liquid is admitted to the sealing means and which is exposed to the interior of the casing and a second leg through which liquid media is discharged from the sealing means and which connects with the liquid media outlet means. 110

In testimony whereof, I have hereunto subscribed my name this 22nd day of March, 1928.

JOHN P. RATHBUN.
